UNITED STATES PATENT OFFICE.

JAMES L. KINSELL, OF BELLE PLAINE, IOWA.

PUNCHING AND RIVETING MACHINE.

SPECIFICATION forming part of Letters Patent No. 630,359, dated August 8, 1899.

Application filed December 30, 1898. Serial No. 700,688. (No model.)

To all whom it may concern:

Be it known that I, JAMES L. KINSELL, a citizen of the United States, residing at Belle Plaine, in the county of Benton and State of Iowa, have invented certain new and useful Improvements in Punching and Riveting Machines; and I do hereby declare that the following is a full, clear, and exact description of the same, reference being had to the annexed 5 drawings, making a part of this specification, and to the letters of reference marked thereon.

The present invention has for its object to provide a simple, cheap, and durable as well as practically operating machine for punching and riveting leather, such as used in harness or other like material where solid or hollow rivets are required.

The invention consists in a machine constructed substantially as shown in the drawings and hereinafter described and claimed.

Figure 1 of the drawings is a side elevation of a machine constructed in accordance with my invention; Fig. 2, a sectional elevation, on an enlarged scale, taken on line $\alpha\alpha$ of Fig. 1, 25 showing the strips of leather or other material after being perforated in position to be riveted together; Fig. 3, a detail perspective view of the adjustable swage; Fig. 4, a perspective view of the hollow rivet, and Fig. 5 30 a perspective view of the solid rivet.

In the accompanying drawings, A represents a suitable support or base, to which is connected a standard B of any preferred construction. To this standard are connected 35 the several operating parts of the machine, which are designed to punch the hole in the material and afterward engage the rivet and secure it to the two strips of leather or other material. The hand-lever C is suitably pivoted to the standard B and is provided with a depending swinging punch-carrier D, the rotatable punch being shown at E and comprising a plurality of punches of different sizes that may be brought in position to punch 40 a hole of the desired diameter as required by the diameter of the rivet. A metal plate α upon the base or support A is located directly under the punch and in line therewith, upon which the material rests when being punched. 45 The shaft F, which carries the swage G, extends up through an elongated opening in the hand-lever C and up through the standard B,

and said shaft is pivoted to the hand-lever, as shown at b. The shaft F also passes down through a guide-arm H, which arm projects 55 out horizontally from the standard B and is of sufficient length to come on line with and over the yielding and adjustable supporting-plate I. The swage is adjustable and reversible to bring it in position to be used with 60 solid or hollow rivets.

In Fig. 2 of the drawings the swage G is in position to act upon a hollow rivet, said rivet, as shown at c, resting upon the block K and ready to engage itself with the perforation in the two strips $d\ e$, of leather or other material.

In order to render the swage G adjustable, it is pivotally connected to the lower end of the shaft F by means of the pin f, extending 70 through an elongated slot g in the swage.

The conical-socketed end of the swage G, which in Fig. 2 of the drawings is shown at the upper end of the swage, is designed for use with the solid rivet h, as illustrated in Fig. 5. 75

The supporting-plate I is automatically raised to its normal position by means of the spring L after said plate has been depressed by the hand-lever C.

After the hole has been punched in the material by means of the punch E the punch-carrier D is swung up out of the way, as shown in dotted lines of Fig. 1 of the drawings, where it may be held by the hand or any convenient means. The two strips of material, as 85 indicated at $d\ e$, are placed over and upon the supporting-plate I after the rivet is placed upon the block K.

The position of the parts ready for riveting is shown in Fig. 2 of the drawings, and as the 90 lever C is depressed it will bring the swage G down upon the material and in turn press down the plate I until the riveting is completed, the plate being forced up to its normal position by means of the spring L. 95

The supporting-plate I may be rendered yielding and adjustable in any suitable and well-known manner. In the present instance I have shown elongated slots i upon the sides of the plate, through which pins k extend. 100

Any suitable-sized rivet, either solid or hollow, may be used, provision being made for this by the specially-constructed swage and the different-sized punches, the adjustable

swage and punch being carried by the same hand-lever, thereby materially simplifying the construction of the machine as well as increasing its practicability.

5 The plate I has a depending tubular guide M, which engages the block K, thereby steady-ing and holding in position the plate when the riveting is going on.

Having now fully described my invention, 10 what I claim as new, and desire to secure by Letters Patent, is—

1. A punching and riveting machine consisting of a base, a standard rising therefrom, a vertical shaft, a hand-lever pivotally mounted in the standard and pivotally connected with the shaft, a yielding supporting-plate, a 15 swage on the lower end of the shaft and having a vertical slot to receive a transverse pin by which it is reversibly mounted and having

different forms of dies on its opposite ends, 20 and a guide for the shaft extending substantially horizontally from the standard, as set forth.

2. The combination with a base, of a block thereon, a spring around the block, a housing 25 around the block, a plate having slotted depending portions engaging means on the housing, and a tubular guide depending from the plate and engaging the block within the spring, substantially as described. 30

In testimony that I claim the above I have hereunto subscribed my name in the presence of two witnesses.

JAMES L. KINSELL.
